BALL POINT PEN

Charles K. Lovejoy, Atlanta, Ga., assignor to Scripto, Inc., a corporation of Georgia

Application February 8, 1955, Serial No. 34,416

Term of patent 14 years

(Cl. D74—17)

Fig. 1 is a front elevational view of a ball point pen, showing my new design;

Fig. 2 is a side elevational view thereof;

Fig. 3 is a top plan view; and

Fig. 4 is an enlarged, fragmentary perspective view of the upper portion thereof.

The essential features of my design reside in the portions shown in solid lines on the drawing.

I claim:

The ornamental design for a ball point pen, as shown and described.
